UNITED STATES PATENT OFFICE

PERCIVAL W. JONES, OF WARWICK, RHODE ISLAND, ASSIGNOR TO ROSENHEIM CO., INC., OF PROVIDENCE, RHODE ISLAND, A CORPORATION OF RHODE ISLAND

EXTENSION DEVICE

Application filed March 2, 1929. Serial No. 344,010.

This invention relates to a foldable extension device for a wrist watch strap and the like; and has for its object to provide a clasp for holding the sections in folded position.

A further object of the invention is the provision of a clasp which will be readily resilient for unclasping purposes but which will retain the sections in folded position against such strains as frequently occur in the strap when in use.

A still further object of the invention is the provision of a pivoted fingerpiece member for assisting in moving the sections to unfolded position which member is also provided with means for attaching one end of the strap thereto.

The invention further consists in the forming of resilient fingers by spaced slits in the side walls of the channel sections, which slits extend into the bottom wall of the section to increase the resiliency of the fingers formed by the slits.

With these and other objects in view, the invention consists of certain novel features of construction, as will be more fully described, and particularly pointed out in the appended claims.

In the accompanying drawings:

Fig. 1 is a perspective view of a pair of sections in unfolded position and a portion of the strap attached thereto.

Fig. 2 is a sectional view of the sections in folded position.

Fig. 3 is a sectional view on line 3—3 of Fig. 2.

Fig. 4 is a top plan view of the sections in folded position.

Fig. 5 is a sectional view of the same.

Fig. 6 is a perspective view partially in sections showing the pivoted fingerpiece at the end of one of the strap parts.

Fig. 7 is a perspective view of the member having the fingerpiece thereon.

In the use of wrist watch straps, it is found desirable to provide a foldable extension device which may be unfolded to enlarge the encircling size of the wrist band to permit the wrist watch connected thereto, to be removed from the hand of the wearer without

disconnecting any of the parts and it is further desired to hold these foldable parts together by a resilient clasp which will have sufficient inherent spring of the stock to prevent unclasping of the parts by the usual strains to which a device of this character is subjected. It is also desired to provide a finger-engaging part which may be readily manually engaged to easily unclasp the sections to permit them to be swung on their pivots to unfolded position; and in order to accomplish this desired result I have formed a clasp by providing spaced slits in the side walls of the channel section to form fingerpieces between the slits to engage protuberances on the side edges of a plate section and resiliently hold the sections in folded position and I have also pivoted to the end of one of the sections a member having a fingerpiece extending therefrom which may be readily engaged to cause an unclasping of the sections permitting them to swing one on the other; and the following is a detailed description of the present embodiment of this invention and illustrating the preferred means by which these advantageous results may be accomplished.

With reference to the drawings, 10 designates a channel section having side walls 11 and 12 and a bottom wall 13. The side walls of this section are slit at a point inward from its end as at 14 and 15 to provide between the slits a resilient finger 16 and in order that the resiliency of this finger may be enhanced the slits 14 and 15 extend into the bottom wall 13 as will be apparent from Fig. 1.

A plate section 17 is hinged as at 18 to the channel section and may be folded into the channel section by swinging about the hinge 18 and held in folded position by the arc-shaped protuberances or portions 19 extending laterally from the opposite edges of the section 17 intermediate its ends and engaging with and between the fingers 16 which are likewise arc-shaped to frictionally engage the protuberances throughout their length.

The fingers 16 are bent inwardly and the edges 20 are then reversely curved outward-

ly, as illustrated in Fig. 3, in order to form a flaring entrance for the protuberances on the edges of the plate section 17.

A strap part 21 consisting of a plurality of block links is connected to the channel sections 10 by means of a pivot pin 22 engaging the side walls 11 and 12 thereof, while the strap part 23 is connected between ears 24 bent up from the side of the plate section 17 by a pivot pin 25 engaging the member 26 which has a fingerpiece 27 extending from one edge thereof to overlie the strap part 21 and provide a portion for engagement by the fingernail to lift the section 17 from clasped position to permit it to be swung about its hinge 18 to unfolded position.

The member 26 is shaped to conform to the appearance of the links of the strap part 23 and serves as a terminal or end thereof with wire portions 29 for connecting it to the remainder of the strap part 23 and the member is provided with a pair of eyes 30 extending from its upper surface thru which the pivot pin 25 extends to hold it in position.

25 The section 17 is notched as at 28 in order to prevent the fingerpiece 27 from engaging with the section 17 when the device is in extended position, as illustrated in Fig. 1, and thus prevent the exertion of leverage by a pull on the strap 13, between the connections of the member 26 and the section 17 which might injure the parts.

The foregoing description is directed solely towards the construction illustrated, but I desire it to be understood that I reserve the privilege of restoring to all the mechanical changes to which the device is susceptible, the invention being defined and limited only by the terms of the appended claims.

40 I claim:

1. An extension device for a wrist strap comprising a plurality of sections hinged together to fold one over the other, portions extending laterally from the opposite edges of one of said sections intermediate its ends, and arch-shaped resilient fingers on another of said sections between which said portions may snap to hold said section in folded position, said fingers being arc-shaped in the longitudinal direction of said sections.

2. An extension device for a wrist strap comprising a plurality of sections hinged together to fold one over the other, arc-shaped portions extending laterally from the opposite edges of one of said sections intermediate its ends, and resilient fingers on another of said sections between which said portions may snap, said fingers being arc-shaped in the longitudinal direction of said sections to engage the said portions along an extended surface and hold said section in folded position.

3. An extension device for a wrist watch strap comprising a pair of sections hinged together to fold one on the other, one of said sections being in plate form with protuberances

on its opposite sides and positioned adjacent but spaced from its free end, the other section being channel shape in cross section with each of said channel walls having a pair of spaced slits forming between the slits a resilient finger, said fingers being positioned to extend over said protuberances when snapped therebetween.

4. An extension device for a wrist watch strap, comprising a pair of sections hinged together to fold one on the other, one of said sections being in plate form with arc-shaped bulging portions extending from its opposite sides and positioned adjacent but spaced from its free end, the other section being channel shaped in cross sections with each of said channel walls having a pair of spaced slits extending a short distance into the bottom of said channel section forming between the slits a resilient finger, said fingers being curved on substantially the arc of said bulging portions to engage the same throughout the curved surface and bent inwardly and outwardly at their edges to receive and extend over said bulging portions when snapped therebetween.

5. An extension device for a wrist watch strap, comprising a pair of sections hinged together to fold one over the other, means for releasably retaining said sections in folded position, ears on one of said sections, a member pivoted in said ears, a fingerpiece extending from said member for manual engagement to unfold said sections, and a notch in the end of said sections to prevent engagement of said fingerpiece and section when in unfolded position.

6. An extension device for a wrist watch strap comprising a pair of sections hinged together to fold one on the other, one of said sections being in plate form, the other section being channel shape in cross section with each of said channel walls having a pair of spaced slits forming between the slits a resilient finger, said fingers being positioned to extend over the edges of said plate section when snapped therebetween.

7. An extension device for a wrist watch strap comprising a pair of sections hinged together to fold one on the other, one of said sections being in plate form, the other section being channel shape in cross section with each of said channel walls having a pair of spaced substantially parallel slits forming between the slits a resilient finger, said fingers being inclined inwardly to extend over the edges of said plate section when snapped therebetween.

8. An extension device for a wrist watch strap, comprising a bottom section and a top section hinged together with the top section overlying the bottom section, means for releasably retaining said sections in folded position, and a member having a finger extension for manual engagement pivoted to the outer surface of the free end of said top

section for lifting or pulling the free end of the top section away from the bottom section.

9. An extension device for a wrist watch strap, comprising a bottom section and a top section hinged together with the top section overlying the bottom section, means for releasably retaining said sections in folded position, ears on the top section adjacent its free end and extending outwardly therefrom, a member pivoted in said ears and a finger-piece extending from said member for manual engagement to lift or pull the free end of the top section away from the bottom section.

15 In testimony whereof I affix my signature.
